201,871

PARTITION

Arnon Hiller, Kew Gardens, N.Y., assignor to United States Plywood Corporation, New York, N.Y., a corporation of New York

Filed Feb. 18, 1964, Ser. No. 78,680

Term of patent 14 years

(Cl. D13—1)

FIG. 1.

FIG. 2.

FIG. 1 is an elevation of a partition showing the new design, the center thereof being broken away to indicate indeterminate length.

FIG. 2 is a top plan view thereof.

I claim:

The ornamental design for a partition, as shown and described.
